NUT BLANKING MACHINE

Samuel Baxendale, Detroit, Mich., assignor, by direct and mesne assignments, to The Modern Collet & Machine Company, Ecorse, Mich., a corporation of Michigan

Application January 19, 1931, Serial No. 509,825

8 Claims. (Cl. 29—53)

The invention relates to nut blanking machines of that type in which a bar of stock is intermittently advanced within a rotating spindle, being clamped during intervals between advancements and while thus clamped being operated upon by tools for boring, shaping and cutting off. The diameter of the nut is determined by the cross section of the stock bar and its length or thickness by the amount it is advanced between clamping operations. Also the movement of the drill which bores the blank must be regulated to correspond to this length or thickness.

In the present state of the art machines of this character have been provided with automatic means for performing the several functions in proper sequence, but whenever the size of the nut is changed various adjustments are necessary. These adjustments require the attention of a skilled workman which increases the cost of manufacture. Furthermore, some of the parts of the mechanism employed are of a character to require frequent adjustment or repair. It is therefore the primary object of the present invention to simplify the construction of the machine and particularly to so simplify the adjustments for changing from one size of blank to another that these may be performed by ordinary unskilled workmen and quickly accomplished. A further object of the invention is to improve the construction of various parts of the mechanism rendering such parts more durable and more accurate in the performance of their respective functions. With these and other objects in view the invention consists in the construction as hereinafter set forth.

In the drawings:

Figure 1 is a sectional side elevation of my improved machine;

Figure 2 is an enlarged longitudinal section through the mechanism for clamping the stock in the rotating spindle;

Figure 3 is a cross section on line 3—3 of Figure 2;

Figure 4 is a cross section on line 4—4 of Figure 2;

Figure 5 is a plan view of the parts shown in Figure 4;

Figure 6 is a cross section on line 6—6 of Figure 1;

Figure 7 is a plan view thereof;

Figure 8 is a cross section on line 8—8 of Figure 1;

Figure 9 is a plan view thereof.

The general construction of my improved machine is similar to machines of the type that

have heretofore been made comprising a bed or frame A on which is mounted an electric motor B having its rotor shaft C extending from opposite ends and coupled with change gear trains (not shown) within the housings D and D'. Extending 60 longitudinally through the housing D is the work carrying hollow spindle E which is rotated at suitable speed by the gear train in said housing. In axial alignment with the spindle E is a drill spindle F which is revolved at the desired speed 65 through a connection with the gear train in the housing D'.

The work spindle E which as before described is hollow has arranged therein an inner sleeve G for operating a radially contractible collet H for clamping the stock. This collet is preferably formed with a conical head portion H' for engaging a correspondingly tapered conical recess I in a collar I' at the end of the spindle E. The collet is slotted longitudinally to form a plurality of, preferably three, segments suitably fashioned on their inner faces to engage the polygonal outer face of the stock bar and the arrangement is such that when the conical head of the collet is drawn inward into the conical recess I it will be contracted to clamp the outer face of the bar and hold the same fixed in relation to the spindle. Inasmuch as various sizes of stock bars are used the collet H is exchangeable, having a threaded engagement at H² with 70 the sleeve G and thus whenever the change in size of blank is desired the collet may be detached and replaced by one of the proper size.

The sleeve G extends to the outer end of the hollow spindle E and has mounted on this end 75 preferably by a threaded engagement therewith, the thrust bearing collar J. This may be adjusted in position on the threads and locked by a lock nut J'. Upon the spindle E is a collar K having a plurality of pivoted cam levers K' 80 therein which as hereinafter described are operated to bear against the thrust collar J and to move the sleeve G for clamping the collet as previously described.

Heretofore stock clamping devices have been 100 constructed employing the elements thus far described, but difficulty has been encountered, first, in successfully using more than a single pair of cam levers; second, in equally dividing the load upon these cam levers and third, in 105 avoiding rapid wear. I have overcome these defects by arranging three of the pivoted levers K' equally distributed angularly around the collar K and to insure an equal loading of these levers have provided a universal pivotal thrust bearing 110

for engagement therewith. Thus, as shown, the member J is provided on its rear face with a spherical segment J² which is engaged by a spherically concaved annular thrust member J³. The 5 inner face of this member J³ is in a plane and directly receives the thrust from the cam levers K'. Also the nose portions K² of the cam levers K' are preferably rounded or of a curve having no longer radius than that of the face J², so that 10 whenever the levers K' are actuated the member J³ will adjust itself on the spherical bearing J² to transmit equal pressure from each of the levers.

For actuating the levers K' a grooved collar L 15 is sleeved upon the spindle E and is provided at its forward end with a flaring portion L' which engages the inner ends of the levers. The collar L is actuated by a lever M bifurcated to embrace the collar and engaging the groove 20 thereof by roller bearings M'. This lever is fulcrumed upon a bracket M² on the frame and is actuated through the medium of a roller M³ by a cam groove M⁴ in the peripheral face of a drum M⁵ actuated by the mechanism within the housing D. This cam is so timed with the other parts 25 of the mechanism hereinafter to be described as to periodically actuate the collar L and through the levers K', thrust bearing J and sleeve G operate the collet H to clamp the stock bar therein.

30 The bar of stock may be of any length and is fed inward into the hollow spindle E whenever the collet is unclamped to permit such movement. The feed mechanism for the bar comprises a hollow guide tube N of sufficient length 35 to receive the longest bar and slotted on its under side for the passage of a pin N'. This pin is attached to a follower N² which slides within the tube N but bears with its forward end against the end of the stock bar. The pin N' outside of 40 the tube N is attached to a cable O which passes over a sheave O' and then to a winding drum O² mounted on the frame of the machine. The drum O² is hollow and has housed therein a spiral spring O³ which is wound up and placed under 45 tension when the cable O is drawn outward, this tension being sufficient to feed the stock bar inward through the guide tube N.

The tools for fashioning and cutting off the 50 end of the stock bar to form a nut blank are of any suitable construction but as shown comprise the cutter P for chamfering the top side of the nut and for cutting a clearance in the polygonal corners on the bottom side of the adjacent nut. There is also a cutter P' for completing the severing of the nut from the stock 55 bar. These cutters are mounted upon slides P² P³ which are actuated by cams P⁴, P⁵ driven by the mechanism within the housing D and suitably timed.

60 The thickness of the nut blank is determined by the amount of longitudinal movement imparted to the stock bar each time that it is released by the unclamping of the collet H. It is also necessary that the depth of the hole which is drilled in the nut blank should substantially correspond 65 with this length of feed. Furthermore, whenever the thickness of the nut is changed provision must be made for a corresponding change in the length of feed of the stock bar and the depth of drilling. 70 My improved mechanism takes care of all of these functions by an exceedingly simple construction easily adjusted and which is as follows:

The drill spindle F is provided with a drill chuck 75 F' for receiving drills of various sizes and is jour-

naled in bearings F² which permit both of rotation and longitudinal movement of the spindle. Clamped upon the spindle between these bearings is a collar Q having a projecting lug Q' pivotally connected to a lever Q² by a pin Q³. The lever Q² is centrally longitudinally slotted at Q⁴ to receive a sliding bar Q⁵ pivotally engaging a pin Q⁶ on an adjustable fulcrum member Q⁷. The member Q⁷ engages a dovetail slot in a stationary bar Q⁸ and is adjusted in this slot by a screw Q⁹ engaging the threaded aperture in the block Q⁷ and swiveled at Q¹⁰ on the stationary frame. Thus by rotating the screw Q⁹ the pivot Q⁶ or fulcrum for the lever may be moved towards or from the pin Q³. The opposite end of the lever is bifurcated to receive a roller bearing R which on one side is engaged by a spring pressed plunger R' and on the other side by a rod R² which latter is actuated by a cam R³ to reciprocate the lever and through it the spindle F. The cam is timed with the rest of the mechanism and imparts a constant length of movement to the rod R² but by adjusting the screw Q⁹ the amount of movement imparted to the spindle F can be varied to any extent between fixed limits. The cam is also fashioned with a portion R⁴ which causes a dwell or rest in the reciprocating movement of the lever in a position intermediate its ends for a purpose hereinafter explained.

105

Operation

To adjust the machine for operation in the manufacture of any particular size of nut blank a collet H suitable for a stock bar of the proper cross section is selected and engaged with the 110 sleeve G. A suitably sized drill is also selected and engaged with the drill chuck F' and the throw of the lever Q² is determined by adjustment of the screw Q⁹ which shifts the fulcrum bearing Q⁶ in the slot Q⁴. Thus the length of reciprocation of the drill spindle F is proportioned to the thickness of the nut blank which is to be formed. However, the length of this reciprocation is somewhat greater than the thickness 115 of the nut so as to provide clearance for disengagement of the nut after it has been severed but the length of reciprocation between the portion R⁴ of the cam and one end of the movement corresponds to the nut thickness.

After proper adjustment is made the stock bar 120 is inserted in the guide tube N with its forward end engaging the sleeve G. A follower N² is then drawn backward, the cable O being unwound from the spring actuated drum O² to permit of this movement, and the end of the follower 125 is inserted in the guide tube N, the pin N' engaging the slot in said tube. This will place a sufficient tension upon the end of the stock bar to feed it forward whenever free to move. The forward movement of the bar is limited by engaging the end of the drill in the position where the portion R⁴ of the cam R³ is in engagement with the roller R. In this position the portion of the stock bar projecting beyond the cut-off knife P' is 130 equal to the desired thickness of the blank and as previously described this thickness may be varied by adjustment of the screw Q⁹.

When the machine is started in operation the sequence of operations is as follows:

First, the lever M is actuated by the cam M⁵ 145 to slide the sleeve L upon the spindle E in a direction causing the flaring end portion L' to engage the ends of the cam levers K' and move them inward. This causes the nose portions K² 150

of the levers to move the bearing J rearward carrying with it the sleeve G and collet H. As has been fully described, the universal movement of the member J³ on the spherical bearing J² will distribute the load equally between the several levers K' and as these are spaced at equal angles around the spindle, they are symmetrically arranged with respect to the axis of the latter and the sleeve G. This avoids overloading of any one lever and lessens wear. The movement of the collet H is only sufficient to effect the clamping of the same against the sides of the stock bar, thereby holding it rigid in relation to the spindle. Following this clamping of the stock, the drill spindle F is moved by the cam R³ and lever Q² to feed the drill into the end of the stock bar and to drill a hole of the proper depth. The cam P⁴ then operates the bar P² to cause the tool P to chamfer the end of the stock bar after which the cam P⁵ actuating the bar P³ moves the cutting off tool P' inward to sever the blank from the bar. Before the completion of this severing movement the drill spindle has been moved in the opposite direction to withdraw the drill from the bored hole with sufficient clearance so that the nut blank when severed will be free to drop. The spindle is then again moved towards the stock until the portion R⁴ of the cam is reached which holds the drill in a position to form a stop for the stock bar and to gauge the thickness of the next nut blank. The cam M⁵ then actuates the lever M to release pressure of the cam levers K' on the bearing J, thereby releasing the clamping action of the collet H and permitting the stock bar to be fed forward by the tension of the spring O³ until movement is arrested by the drill. This completes the cycle which is automatically repeated until the entire bar is used up. Another stock bar is then introduced into the tube N and the operations continued.

A very important feature of my improvement is the ease with which the machine may be adjusted to change from one size of nut blank to another. This requires no changing of cams or any adjustment other than that of the screw Q⁹ which reduces or lengthens the reciprocation of the drill spindle F. Thus any workman without special mechanical skill can easily change the machine when necessary.

Another important feature of my improvement is the use of cam levers which are distributed around the work spindle and which engage a universal pivotal bearing so as to be equally loaded. This not only forms a much more positive actuation of the collet but also greatly lengthens the life of the parts by eliminating wear incidental to overloading any one member.

In the feeding of the stock bar by the mechanism described, there is an inertia element in the drum and cable which delays the acceleration of the stock bar and thus limits the rapidity of its movement. To overcome this I preferably interpose a spring O⁴ between the cable O and the pin N'. This spring will be extended and placed under tension when the follower is first engaged with the stock bar and whenever the clamping collet is released the spring O⁴ will immediately feed the stock bar forward and before the inertia of the drum is overcome. Thus when the machine is used for rapid operation the time required for the feeding of the stock is reduced by this device.

What I claim as my invention is:

1. The combination with a revolute spindle for receiving a stock bar and a collet for inter-

mittently clamping said bar within said spindle, of means for feeding said bar through said spindle when released by said collet comprising a spring actuated rotary drum, a cable wound on said drum adapted to be drawn off the same against the tension of said spring, and a follower for engaging the end of the stock bar attached to the end of said cable.

2. The combination with a revolute spindle for receiving the stock bar and a collet for intermittently clamping said bar within said spindle, of means for feeding the bar longitudinally in said spindle when released by said collet comprising a spring actuated drum, a cable wound on said drum and adapted to be drawn off the same against the tension of said spring, a slotted guide tube in which said stock bar is supported, a follower insertable in said guide tube to engage the end of the stock bar and a connection between the end of said cable and said follower passing through the slot in said guide tube.

3. The combination with a revolute spindle for receiving a stock bar and a collet intermittently actuated to clamp said bar, means for feeding the stock bar through said spindle when released by said collet, means for fashioning and cutting off a projecting end of said stock bar when clamped by said collet, a drill and drill spindle for boring said stock bar, means for reciprocating said drill spindle to effect the drilling and to withdraw the drill, a reciprocating member for actuating said drill spindle arranged parallel thereto and having fixed limits of reciprocation, a lever intermediate said actuating member and said drill spindle connected thereto at its opposite ends respectively, a fulcrum engaging said lever intermediate its ends and means for shifting the fulcrum of said lever while mounted to vary the stroke of the spindle without change in the stroke of the actuating member.

4. The combination with a revolute spindle for receiving a stock bar and a collet for intermittently clamping said bar, of means for advancing the bar through said spindle when released by said collet, means for severing a blank from the projecting end of said bar while clamped by said collet, a reciprocatory drill spindle in axial alignment with said revolute work holding spindle, a drill carried by said drill spindle forming in one position of the latter a stop for limiting the advancement of the stock when released by said collet, a reciprocating member having a constant length of stroke arranged parallel to said drill spindle, a lever forming an intermediate connection between said reciprocating member and said drill spindle and connected thereto at opposite ends respectively, and a fulcrum for said lever adjustable independently thereof to vary the length of reciprocation of said spindle and to correspondingly vary the position of the drill when acting as a stop for the stock bar.

5. The combination with a revolute work holder, means for feeding a stock bar through said holder and means for intermittently clamping the bar to said holder, of means for cutting off a blank from the projecting end of said bar while clamped in said holder, a drill spindle and a drill therein for boring said blank before the severing of the same, a reciprocating member for actuating said drill spindle arranged parallel thereto, a cam for actuating said reciprocating member and for imparting to the same a fixed length of stroke with a dwell at a point intermediate the ends of the stroke, a lever for communicating the reciprocation of said member to the

- drill spindle and a fulcrum for said lever adjustable independently thereof to vary the stroke of said spindle, and to correspondingly vary the position of the drill during the dwell between limits of reciprocation whereby the drill forms a stop for the advancement of the stock and engages the thickness of the blank cut off, said fulcrum engaging a slot in said lever, a fixed bearing in which said fulcrum is adjustable longitudinally of said lever and a screw for adjusting said fulcrum in said fixed bearing. 80
6. The combination with a revoluble spindle for receiving a stock bar and a collet for intermittently clamping said bar within said spindle, of means for feeding said bar through said spindle when released by said collet comprising a spring actuated rotary drum, a cable wound on said drum adapted to be drawn off the same 85 against the tension of said spring, a follower for engaging the end of the stock bar and a spring intermediate said follower and the end of said cable for the purpose described. 90
7. The combination with a revoluble work holder, means for feeding a stock bar through said holder and means for intermittently clamping the bar to said holder, of means for cutting off a blank from the projecting end of said bar while clamped in said holder, a drill spindle and a drill therein for boring said blank before the severing of the same, spaced bearings in which said spindle is longitudinally and rotatively movable, a collar secured to said spindle intermediate said bearing, a reciprocating member for actuating said drill spindle arranged parallel thereto, a cam for actuating said reciprocating member and for imparting to the same a fixed length of stroke with a dwell at a point intermediate the ends of the stroke, a lever pivotally secured at one end to said collar and pivotally engaging said reciprocating member at its opposite end, said lever being slotted longitudinally intermediate its ends, a block slidably engaging said slot, a fulcrum pin pivotally engaging said block, a member to which said pin is secured, a fixed bearing slotted in a 105 direction longitudinally of said lever for receiving said member, and a screw engaging said member to adjust the same in said slot. 100
